DESIGN FOR A BEAUTICIAN'S TRAY

William Nussbaum, New York, N. Y.

Application May 22, 1948, Serial No. 146,516

Term of patent 3½ years

(Cl. D86—10)

To all whom it may concern:

Be it known that I, William Nussbaum, a citizen of the United States, residing at New York, in the county of New York and State of New York, have invented a new, original, and ornamental Design for a Beautician's Tray, of which the following is a specification, reference being had to the accompanying drawing, forming a part thereof.

In the drawing:

Fig. 1 is a top perspective view of a beautician's tray, showing my new design;

Fig. 2 is a bottom plan view of the same;

Fig. 3 is an enlarged vertical sectional view taken on the line 3—3 of Fig. 1; and

Fig. 4 is another enlarged vertical sectional view taken on the line 4—4 of Fig. 1.

I claim:

The ornamental design for a beautician's tray, as shown.

WILLIAM NUSSBAUM.
